UNITED STATES PATENT OFFICE.

GREGORY K. BLOCK, OF NEW YORK, N. Y.

TYPEWRITING MACHINE.

Application filed January 29, 1926. Serial No. 84,604.

My invention relates to typewriters and has a particular reference to keyboard mechanisms for same.

The object of my invention is to provide a keyboard mechanism which would be easy to operate, easy to assemble and to take apart and simple in construction, each individual part being removable without taking apart the rest of the mechanism.

My invention is more fully illustrated in the accompanying specification and drawing in which—

Fig. 1 is an elevation of my keyboard mechanism partly in section, Fig. 2 is a partial plan view, and Fig. 3 is a partial front view of my typewriter keyboard mechanism, and Fig. 4 is a partial view of a modified mechanism.

My typewriter consists of keys 1 with key bars 2 made of flat metal of a uniform thickness and adapted to slide in slots 3 in spacing bars 4 attached at the ends with screws 5 to typewriter frame members 6.

The other end of each bar has a slot 7 resting on a knife 8. A second knife 9 rests against the upper edge of the bar. The knife 9 is attached to arms 10 mounted on a shaft 11 journaled in the frame members 6. A handle 12 is attached to one end of the arm 10. A flat spring 13 tends to keep the arm 10 with the knife 9 pressed against the bar 2.

The bars 2 are connected by pivots 14 with links 15, the other ends of which are connected with rocking plates or segments 16 by pivots 17. The rocking segments are provided with slots 18 with which they rest on knife edge of a steel bar 19. This knife bar is attached to a slotted bar 20 fastened at the ends to the frame members 6 with screws 21. The slots 22 serve to guide the segments and to keep them separated.

The bar 20 is provided with lugs 23 to which springs 24 are attached. The other ends of these springs are connected with the rocking segments 16.

These springs tend to keep the segments turned to the left, raising the bars 2 up. Pivots 25 connect segments with rods 26, pivoted at the other end with pivots 27 to lugs 28 of type bars 29. The other or operating ends of type bars rest on a rod 30 covered with rubber 31.

In order to prevent the segments 16 from chattering or jumping from the knife 19, a retaining strip 32 is placed in a circular slot

33 concentric with the point of the knife 19. Instead of the strip 32 in the slot a similar strip 32' may be placed on the outside of the segment which in this case must be curved concentrically with the point of the knife 19 as shown in Fig. 4.

The type bars 29 are mounted on a rod or wire 34 placed in a slot 35 in a supporting type bar segment 36. Each type bar has a slot 37 for the wire 34. This slot is curved towards the outer end of the bar, so that a pull on the rod 26 tends to retain the bar on the wire 4 and to prevent its sliding off. This slot, however, helps to take the mechanism apart, as each bar can be removed separately without disturbing the wire 34 or the other bars.

The bar has a type 38 with which it strikes the paper drum 39. The end of the bar 75 near its pivoting point on the wire 34 has a cam shaped extension or lug 40. This lug presses against a plate 41 which can slide with arms 42. These arms are connected to a ratchet mechanism (not shown) controlling the movement of the paper carriage 80 with the drum 39.

The bars 29 are arranged in a semicircle, as shown in Fig. 3. The segments 16 are also arranged in a semicircle of a larger radius, as shown in the same Fig. 3.

It is possible, however, to mount the segments on a knife, concentric with the curve of the type bars.

A guide bracket 43 is placed in the middle 90 of the type segment 36 in order to guide the upper portions of the bars 29 when they are striking the paper drum 39.

The operation of my typewriting machine is as follows.

When any of the keys 1 is depressed by the operator, the bar 2 moves down and pulls with it the link 15. The latter turns the segment 16 around its pivoting point which is the edge of the knife 19, and pulls in turn 100 the rod 26. This rod, being connected to the lug 28 of the type bar 29, swings the latter around its pivot which is the wire rod 34, until the type 38 strikes the paper drum 39.

The bar 29 cannot slide off the wire 34, as 105 both sides of the slot 35 are curved at an angle in a direction of the pull exerted by the rod.

During the operating stroke of the type bar 29 the cam shaped lug 40 exerts a pressure against the plate 41, displacing same in a direction shown with the arrow "A" un-

til it takes the position shown with dotted lines in Fig. 1. The plate 41 is attached to lugs or arms 42 connected with the ratchet mechanism (not shown) of the carriage movement mechanism. Any suitable carriage moving mechanism may be used, being connected with the arms 42 in such manner, that with each stroke of a type bar 29 the carriage moves one space.

10 The retrieving spring 24 returns the mechanism in its inoperative position with the bar 29 resting against the supporting rod 30, when the key 1 is released.

In order to take the mechanism apart the 15 spring 24 is disconnected, the retaining bar 32 removed, and the type bar 29 released from the engagement with the wire rod 34. For this purpose the bar is pushed against the plate 41 and upwards until the wire 20 passes through the slot 35. The arm 10 is then turned by pushing on the handle 12, thereby releasing the end of the bar 2 which can be removed from the machine together with the segment 16, link 15 and rod 26 with 25 the bar 29. In the same manner these parts can be again placed in the machine in their respective positions, without disturbing the rest of the mechanism.

This feature represents an important advantage of my construction.

It is also possible by removing the rod 30, bar 32 and the wire 34, to remove the complete set of the key and type bars with their connecting parts and segments.

35 In ordinary typewriters usually it is necessary to disconnect some of the connecting links and rods, and as they are riveted to their pivots, such removal is rather difficult.

40 Another advantage lies in the simplicity of the parts and in the small number of them, also in the corresponding ease and simplicity of assembling my machine during its construction with corresponding reduction 45 in the manufacturing cost.

I claim as my invention:

1. In a typewriting machine, the combination with a plurality of type bars, a stationary segment with slots for said type bars, 50 a wire rod attached to said segment and adapted to pivotally support said type bars, a plurality of key bars, operating connections between said type bars and said key bars, means to keep said key bars in a raised position, a knife edged bar forming a lower fulcrum for said key bars, a second knife

edged bar forming an upper fulcrum for said key bars, said key bars being wedged between the edges of said knife edged bars, and a means to press said upper bar against 60 said key bars.

2. In a typewriting machine, the combination with a plurality of type bars, a stationary segment with slots for said bars, a wire attached to said segment and adapted to pivotally support said type bars, a plurality of key bars, operating connections between said type bars and said key bars, a sharp edged bar forming a lower fulcrum for the inner 65 ends of said key bars, a second bar on top of said key bars, arms supporting said second bar and pivotally connected with the sides of the machine frame, operating handles on said bar, and springs adapted to press said bars against said key bars.

70 3. In a typewriting machine, the combination with a plurality of type bars, a stationary segment with slots for said type bars, a wire attached to said segment and adapted to pivotally support said type bars, 80 lugs on said type bars, bars pivotally connected with said lugs, rocking segments with angular slots at their lower portions, a sharp edged bar adapted to support said rocking segments at said angular slots, pivots connecting said rocking segments with said bars, a plurality of links pivotally connected with said rocking segments, a plurality of key bars pivotally connected with the other ends of said links, and retrieving springs for 85 said rocking segments.

90 4. In a typewriting machine, the combination with a plurality of type bars, a stationary segment with slots for said type bars, a wire attached to said segment and adapted to pivotally support said type bars, lugs on 95 said type bars, connecting bars pivotally connected with said lugs, rocking segments with angular slots at their lower portions, a sharp edged bar adapted to support said rocking segments at said angular slots, a guiding bar adapted to keep said rocking segments in an engagement with said sharp edged bar, a plurality of key bars, links pivotally connecting said rocking segments with said key bars, and a plurality of springs adapted to keep 100 said key bars in a raised position.

105 Signed at New York, in the county of New York and State of New York, Jan. A. D., 1926.

GREGORY K. BLOCK.
